I. LEIBOWITZ

CALENDAR

Filed Oct. 10. 1923

INVENTOR

Isaac Leibowitz,
BY
Fraenkel and Richards,
ATTORNEYS

UNITED STATES PATENT OFFICE.

ISAAC LEIBOWITZ, OF BROOKLYN, NEW YORK.

CALENDAR.

Application filed October 10, 1923. Serial No. 667,603.

To all whom it may concern:

Be it known that I, ISAAC LEIBOWITZ, a citizen of the United States, residing at Brooklyn, in the county of Kings and State 5 of New York, have invented certain new and useful Improvements in Calendars; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention relates, generally, to improvements in calendars, and the invention has for its principal object to provide a novel construction of calendar provided with a rotary date carrying element in combination with which is provided a novel construction of adjustable marker adapted to cooperate with said date carrying element to mark or indicate a specific date thereon, said marker also having means for 20 indicating the month data, etc.

Other objects of this invention, not at this time more particularly enumerated, will be clearly understood from the following detailed description of the same.

25 The invention is clearly illustrated in the accompanying drawings, in which:—

Figure 1 is a front elevation or face view of the novel calendar, made according to and embodying the principles of this invention; Figure 2 is a part side elevation or edge view and part vertical longitudinal section of the same; and Figure 3 is a fragmentary face view of the main body of adjustable marker element removed from operative association with the calendar body.

Similar characters of reference are employed in all of the hereinabove described views, to indicate corresponding parts.

Referring now to said drawings, the reference character 1 indicates a base or back member upon which the novel rotary date carrying element and associated adjustable marker device are mounted.

The reference character 2 indicates the rotary date carrying element, the same comprising a disk-like body of substantially rigid material, such as card-board or the like. Fixed in connection with the upper portion of said base or back member 1 is a journal stud 3 which projects outwardly from the face of said base or back mem-

ber, and upon which said disk-like body is centrally mounted so as to freely turn or rotate thereon. A keeper washer 4 is interposed between the head of said stud 3 and the disk-like body to securely retain the latter against accidental displacement from said journal stud.

The face of said disk-like body 2 is divided into a plurality of concentric panels or divisions, corresponding in number to the number of months in the calendar year, so that one of said panels or divisions is provided for each month. Said concentric panels or divisions are intersected by a plurality of radial panels or divisions, preferably thirty-two in number, so as to subdivide each concentric panel or division into a series of subdivisions within which are inscribed the days and dates of the several months of the year, leaving one subdivision in each concentric panel or division within which is inscribed the name of the month for each particular concentric panel or division.

Fixed upon the lower portion of the face of said base or back member 1, in central vertical alinement with the center of said disk-like body 2, is a guide-member 5, the face or front portion of which is outwardly spaced from the face of said base or back member 1 so as to provide a vertical guideway 6. The reference character 7 indicates the main body of a marker device, which extends upwardly through said guideway 6, so as to be vertically slidably therein. The upper end of said marker device body 7 is provided with a pointer or indicator member 8, which is disposed to extend radially and upwardly across the lower portion of the disk-like body 2. Preferably the said pointer or indicator member 8 is provided with an opening or window 9, which may be selectively registered at will with any one of the concentric panels or divisions of the disk-like body 2 by sliding upwardly or downwardly the marker device body 7. The front wall of said guide-member 5 is provided with two vertically spaced apart transversely extending openings or windows, to wit, the opening or window 10 and the opening or window 11. The face of said marker device body is provided with two data carrying sections, each section being divided into twelve panels or divisions corresponding in width dimensions to the width dimensions of the concentric panels or

105
110

divisions of the disk-like body 2, and the spacing of the respective sections is such, that when the window or opening 9 of the pointer or indicator member 8 is registered 5 or alined over a given concentric panel or division carrying date data for a given month, the corresponding additional data for the same month inscribed in the divisions of the sections of the marker device 10 body 7 will be disclosed through the respective openings or windows 10 and 11 of the guide-member 5. It will be understood from the above description that a single adjustment of the marker device will not only 15 disclose the desired date data for a given month as provided on rotary element or disk-like body 2 but will also disclose through the windows of the guide-member 5 additional data, such, for example, at the window or 20 opening 10 the numerical sequence and name of the month with which the pointer or indicator element is cooperating, and at the window or opening 11 the holidays occurring in such month.

25 Preferably the innermost concentric panel or division of the disk-like member 2 is devoted to the date data for the first month of January, and then the successive outer concentric panels or divisions are devoted 30 respectively to the succeeding months, so that the initial starting position of the marker-device will be such that the window or opening 9 will register with said innermost concentric panel or division, where- 35 after by pulling down the marker-device body 7 the pointer or indicator member 8 may be moved downward to successively aline its window or opening 9 with the succeeding concentric panels or divisions. The 40 data contained in the respective sections provided on the face of the marker-device body 7 read upwardly so that as the marker device is pulled down the successive divisions containing the data will be disclosed 45 so as to properly correspond with the date data of the particular month indicated on the disk-like member 2 by the indicator or pointer member.

To ascertain and disclose any given day 50 and date of the month, after the marker device is set cooperate with the concentric panel or division of the disk-like member 2 carrying the date data for the desired month the disk-like member is rotated to disclose 55 the day and date of the month desired through the opening or window 9 of the indicator or pointer member 8.

From the foregoing description it will be 60 readily understood that my present invention provides a very simple, convenient and novel calendar structure in a very attractive form, and one which readily coordinates and discloses various data in addition to the day and date.

I am aware that some changes or variations in the described calendar structure 65 may be made without departing from the scope of my present invention; hence, I do not limit myself to the exact arrangements and combinations of the several devices and 70 parts as described in the foregoing specification, nor do I confine myself to the exact details of the construction of the same as 75 illustrated in the accompanying drawings.

I claim:

1. A calendar, comprising a back member, a rotary disk-like member mounted on the face of said back-member, said disk-like member having a plurality of concentric panels corresponding respectively to the 80 months of the year and subdivided radially to contain the day and date indications for the respective months, a vertical guide-member mounted on said back-member below said rotary disk-like member, a vertically adjustable marker device slidably extending through said guide-member, and said marker device having at its upper end an indicator portion for cooperating with the 85 subdivisions of said rotary disk-like member. 90

2. A calendar, comprising a back member, a rotary disk-like member mounted on the face of said back-member, said disk-like member having a plurality of concentric panels corresponding respectively to the 95 months of the year and subdivided radially to contain the day and date indications for the respective months, a vertical guide-member mounted on said back-member below said rotary disk-like member, a vertically adjustable marker device slidably extending through said guide-member, said marker device having at its upper end an indicator portion for cooperating with the 100 subdivisions of said rotary disk-like member, the front wall of said guide member having windows therein, and the face of said marker device having inscribed thereon additional data for disclosure through said 105 windows in correspondence with the given day and date subdivisions of the disk-like member for the particular month with which said indicator portion of said marker device is adjusted to cooperate. 110

3. A calendar, comprising a back member, a rotary disk-like member mounted on the face of said back-member, said disk-like member having a plurality of concentric panels corresponding respectively to the 120 months of the year and subdivided radially to contain the day and date indications for the respective months, a vertical guide-member mounted on said back-member below said rotary disk-like member, a vertically adjustable marker device slidably extending through said guide-member, said marker device having at its upper end an 125

indicator portion provided with an opening adapted to cooperate with the subdivisions of said rotary disk-like member.

4. A calendar, comprising a back member, a rotary disk-like member mounted on the face of said back-member, said disk-like member having a plurality of concentric panels corresponding respectively to the months of the year and subdivided radially to contain the day and date indications for the respective months, a vertical guide-member mounted on said back-member below said rotary disk-like member, a vertically adjustable marker device slidably extending through said guide-member, said marker device having at its upper end an indicator portion provided with an opening adapted to cooperate with the subdivisions of said

rotary disk-like member, the front wall of said guide member having windows therein 20 and the face of said marker device having inscribed thereon additional data for disclosure through said windows in correspondence with the given day and date subdivisions of the disk-like member for the 25 particular month with which said indicator portion of said marker device is adjusted to cooperate.

In testimony, that I claim the invention set forth above I have hereunto set my hand 30 this 6th day of October, 1923.

ISAAC LEIBOWITZ.
